(74) *Attorney, Agent, or Firm* — Banner & Witcoff, Ltd.

(57) **CLAIM**

The ornamental design for a light fixture, as shown and described.

DESCRIPTION

FIG. 1 is a front perspective view of a light fixture showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a front perspective view of the light fixture of FIGS. 1-7 shown in an illuminated state;

FIG. 9 is a front view thereof;

FIG. 10 is a rear view thereof;

FIG. 11 is a right side view thereof;

FIG. 12 is a left side view thereof;

FIG. 13 is a top view thereof;

FIG. 14 is a bottom view thereof;

FIG. 15 is an alternative embodiment identical to the designs of FIGS. 1-14 with the design having an exemplary depicted width and length;

FIG. 16 is an alternative embodiment identical to the designs of FIGS. 1-14 with the design having an exemplary depicted height and length; and,

FIG. 17 is an alternative embodiment identical to the designs of FIGS. 1-14 with the design having an exemplary depicted width and height.

In FIGS. 1-14, the light fixture is shown with a symbolic break in its length, width, and height. In FIG. 15, the light fixture is shown with a symbolic break in its height. In FIG. 16, the light fixture is shown with a symbolic break in its width. In FIG. 17, the light fixture is shown with a symbolic break in its length. The appearance of any portion of the light fixture between the respective adjacent break lines forms no part of the claimed design. The radiating lines emanating from the design in FIGS. 8-14 schematically represent
